Primary Examiner — Kevin Rudzinski*Assistant Examiner* — Sean D Lough(74) *Attorney, Agent, or Firm* — Michael Best & Friedrich LLP(57) **CLAIM**

We claim the ornamental design for an air inlet damper, as shown and described.

DESCRIPTION

FIG. 1 is a bottom perspective view of an air inlet damper showing the new design;

FIG. 2 is a right side view thereof;

FIG. 3 is a left side view thereof;

FIG. 4 is a rear view thereof;

FIG. 5 is a front view thereof;

FIG. 6 is a top view thereof; and,

FIG. 7 is a bottom view thereof.

The broken lines present in all FIG. views illustrate portions of the air inlet damper that is environment and forms no part of the claimed design.

1 Claim, 5 Drawing Sheets# US D771,791 S
